Filed June 17, 1957, Ser. No. 666,155
1 Claim. (Cl. 166—39)

This invention relates to a process for the recovery of oil from oil bearing formations. It is more particularly concerned with the secondary recovery of oil by an in-situ combustion process employing a single well.

The primary recovery of oil from oil bearing formations, hereinafter referred to as pay zones, utilizes the natural pressure on the pay zone to force the oil through the permeable formation of the pay zone to the well. The pressure on the pay zone may be sufficient to deliver oil to the well head or, if the pressure is not adequate, a lift is used to raise oil in the borehole to the surface. Usually only a small fraction of the oil present in the oil bearing formation can be recovered by primary recovery processes. Secondary recovery methods in which the pay zone is repressured to move the oil through the formation are frequently used to increase the amount of oil recovered. The repressuring can be accomplished by the injection of gas into the upper part of the formation or water into the lower part to provide the drive required. In another secondary recovery process referred to as an in-situ combustion process, oil in the formation is ignited and an oxygen-containing gas is pumped into the formation at an input well to continue the burning. The oxygen-containing gas and products of combustion force oil through the pay zone adjacent production well from which the oil is withdrawn.

This invention resides in an in-situ combustion process employing a single well for the production of oil from a pay zone in which the pay zone is fractured and the fracture sealed with an impermeable material to form a barrier extending radially from the well. An oxygen-containing gas is injected into the pay zone above the barrier. Oil in the pay zone is ignited above the barrier and the injection of the oxygen-containing gas continued to force oil radially outward through the pay zone around the barrier and then radially inward to the well below the barrier. In an embodiment of this invention which is particularly advantageous the pay zone is extensively fractured below the barrier, thereby facilitating flow from the pay zone into the well.

The single figure of the drawing is a diagrammatic representation, partially in vertical section, of a well adapted for use in the in-situ combustion process of this invention.

Referring to the drawing, the borehole indicated generally by reference numeral 10 of a well is drilled completely through a pay zone 12 to a total depth 14. Pay zone 12 lies between base rock 16 and an impermeable cap rock 18. The ground surface is indicated in the drawing by reference numeral 20. Casing 22 is set substantially to total depth in the borehole 10 and cemented at 24 completely through the pay zone 12. Any desired arrangement, illustrated diagrammatically by a cap 26, can be used to close the upper end of the casing 22 at the well head. For most effective use of this invention, pay zone 12 should be of substantial thickness, for example more than about 15 feet, in order to provide sufficient room in the lower portion of the bed for two separate radially extending fractures.

The casing 22 is perforated at 28 at the central portion of the pay zone and the formation then fractured at 30 through the perforations 28. The fracture 30 can be

2

made by conventional fracturing techniques such as the technique described in United States Letters Patent No. 2,642,142 of J. B. Clark issued June 16, 1953. And impermeable heat resistant cement such as a high alumina cement is squeezed into fracture 30 to form a barrier 31 extending radially from the well. The elevation of the fracture 30, and hence barrier 31, in the pay zone may vary substantially and the term "central portion" used to describe the position of the fracture 30 only means that the fracture is at an intermediate position between the upper level at which the oxygen-containing gas is injected into the formation and the lower level at which the oil from the formation is delivered into the well. The exact location of the barrier 31 will be influenced by several variables such as the characteristics of the pay zone and the extent of the radial fracture made at a level below the barrier 31. When the pay zone is fractured extensively below the barrier 31, it will be desirable to locate the barrier near the bottom, for example in the lower one-third of the pay zone, to take advantage of gravity segregation and obtain a larger air sweep pattern.

Any plug of cement that may remain in the casing after squeezing cement into fracture 30 is drilled out and the casing 22 is then perforated at 32 slightly above the bottom of the pay zone 12 and below the perforations 28. After the casing is perforated at 32 the pay zone 12 is fractured at 34 through perforations 32.

Fracture 34 is preferably located as near the bottom of the pay zone 12 as possible to allow recovery of the oil in substantially the entire pay zone. It is preferred that the fracture 34 will be within about one-quarter of the thickness of the pay zone from the bottom of the pay zone. A propping agent such as a coarse sand is deposited in the fracture to hold the fracture open to form a channel of large capacity to carry the oil and products of combustion to the well. Because of the very high resistance to flow of a three-phase mixture of gaseous combustion products, condensed water, and oil, through a permeable formation having very small openings the large channels through the fracture greatly reduce the resistance to flow from the formation to the well.

Barrier 31 extends for sufficient distance from the borehole to allow combustion of oil in a major part, preferably substantially all, of the pay zone in the drainage area of the well. In a pay zone in which many wells have been drilled, the well spacing will influence the radial extent of the barrier 31. It is preferred that barrier 31 have substantially the same, or only slightly smaller, radius as fracture 34. Ordinarily fracture 34 will extend for a minimum radius of about 50 feet to a maximum radius of about 600 feet, depending on the characteristics of the particular oil field.

A series of perforations 36 are made in the casing 22 and surrounding cement at intervals through the pay zone above the barrier formed at fracture 30 and perforations 28 for the injection of an oxygen-containing gas in the manner hereinafter described. A heat resistant packer 38 is then set in the casing 22 above the perforations 28 and below the perforations 36 to separate perforations 32 and 36. A tubing 40 is run from the well head through packer 38 to a position with its lower end adjacent perforations 32. Tubing 40 is insulated as indicated at 42 above the packer 38 to protect the tubing from the high temperatures in the casing 22 during ignition of the oil.

An igniter 44, which may be of the type described in United States Letters Patent No. 2,668,592 of J. J. Piros et al., is run in the annular space 46 between the casing 22 and tubing 40 to a position adjacent the perforations 36. Igniter 44 is mounted on the lower end of a pipe 48 through which an oxygen-containing gas such as air or air enriched with oxygen or diluted with an inert gas is

delivered. A fuel line 50 extends downwardly through the pipe 48 and opens at its lower end adjacent the igniter 44. Electric energy for supplying a spark at the igniter 44 is furnished through suitable lead line 52.

Pipe 48 is connected at the well head to a source of the oxygen-containing gas through a line 54. Additional oxygen-containing gas, if required, is supplied through a line 56 opening into the annulus 46. The upper end of fuel line 50 is connected to a source of fuel, such as natural gas or gas from a separator at the lease, not shown.

In the operation of the apparatus illustrated in the figure, a fuel supplied through line 50 and an oxygen-containing gas supplied through the pipe 48 are mixed and the mixture is ignited by igniter 44. The hot products of combustion are forced through perforations 36 into the pay zone and heat the oil in the pay zone to a temperature sufficiently high to start its combustion. Heat to ignite oil in the formation adjacent the perforations 36 can be furnished by means of an electric heater instead of by burning a fuel, if desired. Oxygen-containing gas is supplied in excess of that required by the fuel through line 56 to supply the oxygen for burning oil in the formation.

After combustion of oil in the pay zone 12 has commenced, the flow of fuel is stopped and the flow of oxygen-containing gas continued. The hot products of combustion force oil in the pay zone 12 radially outward past the outer edge of the barrier 31. The oil then moves generally radially inward as indicated by arrows 58 to fracture 34 and then radially inward to the well bore. Oil is delivered from the bottom of the well through tube 40 by any suitable means such as a pump, not shown. Oil from the formation flows inwardly into the area defined by the barrier and fracture in the directions indicated by arrows 60.

In a specific example of this invention a well is drilled to a total depth of 4,010 feet through a pay zone 35 feet thick. The top of the pay zone is at a depth of 3,970 feet. Seven inch casing is set in the well to a depth of 4,008 feet and cemented through the pay zone. The casing is perforated at a depth of 3,994 feet and is fractured with a lease crude oil containing 1 to 2 pounds of sand per gallon for an average radius of 70 feet. A heat resistant cement is squeezed through the perforations into the fracture and pressure is maintained until the cement sets to form a barrier extending radially through the pay zone. A cement plug in the casing is drilled to a depth of 4,007 feet and the casing is perforated at a total depth of 4,003 feet. Lease oil containing 1 to 2 pounds of sand per gallon is used in fracturing the formation through the perforations at 4,003 feet. A fracture about 85 feet in radius is made in the pay zone. The casing is then perforated at intervals between the barrier and the top of the pay zone.

A heat resistant packer is set in the casing immediately above the barrier and tubing is run through the packer to a depth of 4,003 feet. Natural gas and air are introduced into the annulus above the packer and ignited adjacent the series of perforations above the barrier to heat oil above the barrier adjacent the borehole to ignition temperature. The rate of flow of natural gas is 5,000 standard cubic feet per day and of air is 100,000 standard cubic feet per day. The flow of air and natural gas is continued until the temperature of the formation adjacent the casing is 1,000° F. The flow of natural gas is stopped and the flow of air increased in 48 hours to a rate of 150,000 standard cubic feet per day at a pressure of 2,800 pounds per square inch gauge at the well head, and then continued at that rate. Oil delivered through the bottom fracture is lifted through the tubing to the well head.

This invention provides an in-situ combustion process utilizing a single well for increasing the production of oil from a pay zone. The process is particularly valuable when used in fields where, because of well spacing or

other reasons, it would be necessary to release very large quantities of heat in a formation before any of the advantages of the heat could be realized if the conventional input and production well set-up were employed. Any tendency for gravity separation of liquid and gaseous components in the pay zone above the barrier increases the sweep of the gases into the pay zone radially outward from the edge of the barrier and thereby increases the volume of the pay zone affected by the process of this invention. In the embodiment of the invention in which the fracture is near the lower border of the pay zone and the barrier is close to the fracture, control of the characteristics of the fracture allows control of the resistance to flow into the well. By suitable location of the barrier and selection of the size of the fracture and propping agent, the fracture will be substantially full of oil from the surrounding pay zone and the oil is driven to the well with a minimum gas-oil ratio by the pressure of the combustion products.

Heat transfer through the barrier to the lower section of the pay zone reduces the resistance to flow through the lower section of the pay zone by raising the temperature of both the oil and the formation, and is especially advantageous in the embodiment in which the barrier is very close to the fracture. The large area of the cylinder or frustum of a cone outlined by the outer edges of the barrier and fracture allows a large total flow radially inward from the pay zone to the fracture even though the pressure on the pay zone is low.

We claim:

A process for producing oil from a pay zone utilizing a single well penetrating the pay zone comprising forming a first substantially horizontal fracture in the pay zone, said first fracture being in the bottom one-fourth 35 of the pay zone and extending at least 50 feet radially from the well through the pay zone, propping the first fracture open with solid particles, forming a second substantially horizontal fracture above the first fracture, said second fracture extending substantially the same distance into the pay zone as the first fracture and being in the bottom one-third of the pay zone, displacing cement into the second fracture to form a substantially horizontal barrier above the first fracture, setting a packer in the well adjacent the barrier to divide the well into an upper zone above the packer and a lower zone below the packer, running tubing down the well and through the packer to provide a conduit extending down the well to the lower zone, said tubing and the wall of the well defining an annulus above the packer, injecting an oxygen-containing gas down the annulus and into the pay zone immediately above the barrier, igniting oil in the formation above the barrier, continuing the injection of the oxygen-containing gas to continue combustion of oil in the pay zone above the barrier to sweep oil radially outward from the well above the barrier and into the first fracture, delivering oil through the first fracture radially inward to the well, and lifting oil delivered into the well through the first fracture through the tubing string to the surface.
